COMBINED WALL TELEPHONE SUPPORT AND HOLDER FOR A MEMORANDUM PAD AND PENCIL OR SIMILAR ARTICLE

Arthur E. Du Bois, Enfield, Conn.

Application October 18, 1957, Serial No. 48,155

Term of patent 14 years

(Cl. D26—14)

Fig. 1.

Fig. 2.

Fig. 3.

Figure 1 is a side elevational view of a combined wall telephone support, and holder for a memorandum pad and pencil or similar article, showing my new design, the opposite side being substantially a mirror image thereof.

The broken line showing of a telephone, memorandum pad and pencil is for illustrative purposes only.

I claim:

The ornamental design for a combined wall telephone support and holder for a memorandum pad and pencil or similar article, as shown and described.
